UNITED STATES PATENT OFFICE

154,380

DESIGN FOR A COMBINATION SPARK PLUG CLEANER AND TESTER

Gilbert C. Gettelman, Hartford, Wis., assignor to
Globe-Union Inc., Milwaukee, Wis., a corpora-
tion of Delaware

Application August 25, 1948, Serial No. 148,281

Term of patent 14 years

(Cl. D26—5)

To all whom it may concern:

Be it known that I, Gilbert C. Gettelman, a citizen of the United States, residing at Hartford, in the county of Washington and State of Wisconsin, have invented a new, original, and ornamental Design for a Combination Spark Plug Cleaner and Tester, of which the following is a specification, reference being had to the accompanying drawing, forming a part thereof, and in which:

Figure 1 is a perspective view of a combination spark plug cleaner and tester showing my new design;

Figure 2 is a side elevational view thereof;

Figure 3 is a front elevational view;

Figure 4 is a back elevational view; and

Figure 5 is a top plan view.

The dotted line showing of the spark plug is for illustrative purposes only.

I claim:

The ornamental design for a combination spark plug cleaner and tester, substantially as shown and described.

GILBERT C. GETTELMAN.
